UNITED STATES PATENT OFFICE

ANDREW GEDEON, OF CHICAGO, ILLINOIS

RADIATOR

Application filed August 28, 1929. Serial No. 388,973.

The invention relates to radiators of the type adapted to be used in connection with heating plants.

The object of the invention is to provide a radiator, which permits a free circulation of air about each unit of the radiator and having a comparatively great surface as well for absorbing heat from the heating medium as for radiating heat into the room to be heated.

A further object of the invention is to provide a radiator to be composed of a plurality of radiator units having means for permitting all said units to be heated simultaneously or to heat only a part of said units at will.

A still further object of the invention is to provide a radiator consisting of a plurality of radiator units with a plurality of valves arranged at a distance from each other but adapted to be regulated by opening or closing one of said valves.

Other objects of the invention not specifically mentioned may be easily ascertained and understood from the following description in connection with the accompanying drawings forming a part thereof. It is however to be noted that the invention is not to be limited or restricted to the exact construction or formation, shown in the drawings and described in the specification, but that the invention is only to be limited by the scope of the claims appended hereto.

In the drawings illustrating a preferred embodiment of the invention:

Fig. 1 is a top view of a radiator consisting of a plurality of radiator units and partly shown in section. Said section being taken on line 1—1 of Fig. 2.

Fig. 2 is an elevation of a radiator consisting of a plurality of radiator units partly shown in section and partly as a front view, the whole view being taken on line 2—2 of Fig. 1 and

Fig. 3 is a vertical, longitudinal, sectional view of one radiator unit, said section being taken on line 3—3 Fig. 1.

The whole radiator according to the present invention consists of a plurality of radiator units which are to be divided in two different kinds of units, namely end units and intermediate units. As the name indicates the end units are to be placed on the outer ends of the radiator consisting of the single units and the intermediate units are to be placed between said end units.

The end units 5 as well as the intermediate units 6 are preferably formed or shaped alike with some small exceptions, which will be noted later on. The two end units of a radiator, composed of a plurality of units are provided in their bottoms adjacent the one end thereof, which shall be called the rear end, with a hole 7. A flange 8 extends downwardly from the bottom and surrounds said hole and is adapted to be connected by means of fittings such as an elbow 9, a short pipe 10 and a second elbow 11, pipes 12 and a T 13 with the intake pipe 14, which connects at its other end with a boiler (not shown) furnishing the heating medium. According to the present invention a valve 15 is inserted in the pipes 12, so that the flow of the heating medium through said pipes may be regulated by means of said valves. It is to be understood, that these two valves may be replaced by a three-way-valve.

The hole 7 leads into the longitudinal center part of the interior of the end unit, which may be looked upon as forming a comparatively long narrow rectangle, which is enclosed by the walls 16, 17 on one unit and 18 and 19 on the other unit. From this central rectangle narrow blind channels 20 extend at regular intervals sidewise and are surrounded by the walls 21, 22 and 23. The part of the end unit, in which the intake line ends, that is the rear portion, is formed so, that it is as wide as two corresponding channels 20 together, so that the side walls 24 of said end portions will be aligned with the end walls 22 of said channels. In this manner the heating medium will enter into a comparatively great space, permitting it to rise therein easily and quickly to the top of the radiator unit. The heating medium will then fill the whole interior of the unit and will arrive in the forward portion of the unit, which is shaped exactly like the rear portion with the exception that the hole 7 and the flange 8 surrounding the hole is omitted and that in the

side walls 25 of said forward portions exit holes 26 are provided adjacent the bottom of said unit, which are surrounded by outwardly extending nipples 27.

5 In order to increase the heat radiating surface of each unit sidewardly extending flanges 28 are provided.

10 The intermediate radiator units are built practically the same as the end units, but the entrance hole 7 is omitted in the forward part of the unit.

15 In the bottom of the enlarged forward part of the intermediate unit, a drain hole 29 is provided and a nipple 30 extends downwardly from the bottom of said unit and surrounds the drain hole 29. In this manner the interior of the intermediate radiator unit may be connected with a drain or return pipe (not shown). The forward portion of 20 an intermediate unit is enlarged in the same manner as the forward portion of an end unit, and connecting nipples 31 are provided in the side walls of the enlarged forward portion of each intermediate unit. By means 25 of the nipples 27 on the end units and the nipple 31 on the intermediate units, such units may be connected with each other, so that the heating medium entering and filling the end unit may also enter the adjacent intermediate unit. It is understood, that a plurality of intermediate units may be interposed 30 between the two end units of a radiator, and that adjacent intermediate units will then be connected with each other by means of the 35 connecting nipples 31.

Inside each of the connecting nipples 31 a clack valve 32 is provided, which is hingedly attached to the wall of said nipple as indicated at 33. A shoulder 34 is formed in 40 the nipple and serves as valve seat. The valve itself is provided with a counterweight 35 adjacent its free end and urges said valve into open position. In order to prevent the valve from opening too far an abutment 36 45 is provided inside of said nipple.

The radiator described above operates as follows:

When a room is to be heated, in which a radiator, composed of end units and intermediate units according to the present invention, is placed, the two valves 15 are opened so, that the heating medium may flow through the opening 7 into the end units and through the nipples 27 and 31 into the intermediate units, so that the heating medium will enter said intermediate units from both ends. It is selfevident, that the nipples 27, which are not connected with any other units, must be closed by means of plugs 36. Since 50 the pressure against the valves 32 will be the same from both sides, said valves stay into open position because the counterweight 35 will urge the same into said position.

55 If the room gets too warm and it is desired to utilize only a part of the radiator,

one of the valves 15 may be closed, so that the heating medium enters only one of the end units and flows only from one side into the adjacent intermediate unit. When this occurs the pressure exerted by the heating 70 medium will close the valve 32, connecting the intermediate unit arranged next to the end unit with the following unit, so that only the end unit and the adjacent intermediate unit will be heated.

75 It is clear, that by operating the valve 15 the clack valve 32 is controlled in spite of the fact, that these two valves are spaced from each other quite a distance. The heating medium entering the intermediate units 80 returns through the opening 29.

Having described my invention and how the same is to be performed, I claim as new and desire to secure by Letters Patent:

1. A device of the class described consisting of a pair of end units and an intermediate unit, each of said units having a main inner space extending longitudinally of said unit, from which space blind channels extend sidewardly, a nipple on the bottom of each of said units adjacent one end thereof, and communicating with the interior of the corresponding unit, a pair of nipples extending laterally of each unit communicating with the interior thereof and adapted to be connected with an adjacent nipple, a pipe line connected with the nipples in the bottom of the end units and adapted to conduct a heating medium into said units, a valve interposed in said pipe line and regulating the flow of the heating medium and a clack valve arranged in each of the nipples extending laterally from the intermediate units and adapted to be closed by the pressure of the heating medium against one side of said 105 valve.

2. A device of the class described consisting of a pair of end units and an intermediate unit, a nipple on the bottom of each unit adjacent one end thereof and communicating with the interior of said unit, a pair of nipples arranged on the side walls of each unit, communicating with the interior of said unit and adapted to be connected with the nipple of an adjacent unit, a pipe line connected with the bottom nipples of the end units and adapted to conduct a heating medium into said unit, a valve in said pipe line and regulating the flow of the heating medium there-through and into the end units and another valve arranged to control the flow of the heating medium through nipples connecting the adjacent units, said last named valves normally being in open position but adapted to be closed under pressure exerted by the heating medium upon one side of said valve.

In witness whereof I affix my signature,
ANDREW GEDEON.
